(Cl. D58—26)

FIG. 1

FIG. 2

FIG. 1 is a side perspective view of a wine bottle holder, showing my new design; and

FIG. 2 is a top plan view thereof.

The side not shown is substantially a mirror image of the side shown.

The broken line showing of the bottle and attached flower holders is for illustrative purposes only.

I claim:

The ornamental design for a wine bottle holder, as shown and described.
